of Delaware

Application July 18, 1941, Serial No. 402,911

8 Claims. (Cl. 62—5)

This invention relates to refrigeration and more particularly to control of refrigeration apparatus.

It is an object of the invention to provide a refrigerator control responsive to both cooling element and box air temperature conditions in a manner to maintain proper air temperature and effect defrosting.

Various other objects, features and advantages of the invention will be apparent from the following description in connection with the accompanying drawings, in which:

Fig. 1 is a more or less diagrammatic view with parts in vertical section, illustrating a refrigerating system having a control device embodying the present invention.

Fig. 2 is an enlarged vertical sectional view of the control device of Fig. 1.

Fig. 3 shows part of the device of Fig. 2 in a different operative position, and

Fig. 4 is a fragmentary top view of the control device of Fig. 2 with the cover of its casing removed.

The invention is shown in Fig. 1 in connection with a refrigerating system like that described in Patent No. 2,207,838 to A. R. Thomas, issued July 16, 1940, and provided with a heat transfer system like that described in Patent No. 2,182,934 to A. R. Thomas, issued December 12, 1939.

The heat transfer system includes a cooling element 10 disposed in a thermally insulated refrigerator storage compartment 11, and comprising a finned pipe coil 12 connected to a header 13. This heat transfer system also includes a condenser coil 14 connected to the evaporator 10 by a conduit 16, and forming with said evaporator part of a closed fluid circuit containing a suitable volatile heat transfer fluid such as methyl chloride. Condenser coil 14 is disposed below the evaporator 10 and is refrigerated in an evaporator unit 15 forming part of the refrigerating system.

Since the condenser 14 is disposed at a lower level than the evaporator 10, suitable means is employed to raise condensed liquid to said evaporator. For that purpose, a lift device is provided comprising a vessel 17, connected to the lower outlet end of the condenser 14, and a second vessel 21 having its upper part connected to the upper and lower parts of said vessel 17 by conduits 18 and 19 respectively. The lower end of the vessel 21 is in turn connected by a conduit 22 to the receiver 13 for conducting liquid to the evaporator 10. The construction and operation of the lift device 17, 21 is shown and described in said

Thomas Patent No. 2,182,934, hereby incorporated in this description.

The evaporator 15, forming part of the refrigerating system shown in said Thomas Patent No. 2,207,838, has a suitable refrigerant such as ammonia introduced therein through a conduit 5. This ammonia evaporates and diffuses in the cooling unit 15 into an inert gas such as hydrogen to produce a refrigerating effect, which condenses the fluid in the condenser coil 14. The resultant gas mixture of inert gas and refrigerant flows from the lower part of the evaporator 15 through a conduit 26, the outer passage of a gas heat exchanger 27, and a conduit 28 into an absorber 29. In absorber 29, refrigerant gas is absorbed by a suitable liquid absorbent such as water which enters through a conduit 32. The inert gas, which is practically insoluble and weak in refrigerant, is returned to the evaporator 15 through a conduit 33, through a plurality of tubes forming the inner passage of the gas heat exchanger 27, and then through a conduit 34. The enriched absorption liquid is conducted from the absorber 29 through the outer passage of a liquid heat exchanger 35, vessel 36, and analyzer 38 to generator 40.

A coil 42, connected to generator 40 by a pipe 41, is heated by a burner 43, whereby liquid refrigerant is raised by vapor lift action through conduit 44 into a vessel 45, in which refrigerant vapor and absorption liquid are separated. Liberated refrigerant vapor flows downward through a conduit 46 into the generator 40. This vapor together with the refrigerant vapor expelled out of solution in the generator 40 by the heating action of the burner 43, flows through the analyzer 38 into the vessel 36. From vessel 36 the refrigerant vapors flow upward through a conduit 47 and a liquid cooled rectifier 48 into a condenser 50 in which the refrigerant is liquefied. The liquefied refrigerant flows from this condenser 50 through conduits 51 and 52 into the cooling jacket of rectifier 48. From the rectifier 48, liquid refrigerant flows to the evaporator 15 through a conduit 53, coil 54, and conduit 25. In coil 54 liquid refrigerant is pre-cooled by evaporation thereof into enriched gas which flows from and to the gas heat exchanger 27 through conduits 55 and 56.

The weakened absorption liquid from which refrigerant has separated flows from the vessel 45 through a conduit 57, through the inner passage of liquid heat exchanger 35, through the conduit 32 and into the upper part of the absorber 29. The heat liberated with absorption of the re-

frigerant vapor in absorber 29 is transferred to a cooling medium which flows upward through a coil 58. Coil 58 is connected to a conduit 60 extending through the condenser 50, whereby the latter is cooled by the same cooling medium as the absorber 29.

A vessel 61 having an opening 62 in the bottom thereof is arranged in the absorber 29. The upper part of this vessel 61 is connected by a conduit 63 to the upper part of the conduit 52, so that any inert gas which may pass into the condenser 50 can flow into the inert gas circuit. Any refrigerant vapor not liquefied in condenser 50 flows through conduit 63 to displace inert gas in the vessel 61 and force such gas into the inert gas circuit through the opening 62, thereby increasing the total pressure in the system. With such increase in pressure in the system, an adequate condensing pressure is obtained to insure condensation of refrigerant vapor in the condenser 50.

The flow of fuel gas to the burner 43 is regulated by a control device 65 comprising a valve casing 66. The interior of this casing 66 is divided by a flexible diaphragm 67 into an upper chamber 68 and a lower chamber 69. The latter chamber is in turn divided by a valve partition 70 into two valve passages 71 and 72. Communication between these passages 71 and 72 is controlled by a pair of valves 82 and 83 to be described. The lower part of the casing 66 has a gas inlet 73, leading into the passage 71, and connected by a conduit 74 to a suitable source of fuel gas. The lower part of the casing 66 also has a main gas outlet 75, connected to the burner 43 by a conduit 76.

For controlling the gas flow between the inlet 73 and the outlet 75 through the passages 71 and 72, the valve partition 70 has an opening within which is fixed a valve seat member 77 shown in the form of a cylindrical sleeve. This sleeve 77 is provided with a central hub 80 connected to the peripheral section of said sleeve by spaced radial arms 81. The lower and upper ends of the sleeve 77 serve as seats for valves 82 and 83 disposed in passages 72 and 71 respectively. Valves 82 and 83 are formed of any suitable gas resistant material such as artificial rubber commercially known as "DuPrene" or "Thiokol."

The valve 82 is part of a high temperature safety device, which cuts off the flow of gas to the burner 43 under certain conditions, and which comprises a resilient snap-action diaphragm 86 below the seat member 77, and a rigid plate 87 secured between the lower end of the casing 66 and a cover plate 88. Passing through openings in the plates 87 and 88 and secured to said plate 87 is one end of a tube 90, the other end being connected to a thermal bulb 91, arranged in thermal contact with the liquid cooled rectifier 48 as shown in Fig. 1. The tube 90 and bulb 91 are charged with suitable volatile fluid, and with the resilient diaphragm 86 and plate 87 constitute an expansible fluid thermostat.

The resilient diaphragm 86 is adapted to bear against the lower end of a C-shaped leaf spring 93, secured at its upper end to the valve 82. A spiral spring 94 is retained in position between the hub 80 and valve 82 to urge the latter to its normal open position shown in Fig. 2.

If for any reason the temperature of the liquid cooled rectifier 48 becomes relatively high, for instance, due to the failure of the cooling medium to circulate properly through the condenser 50, the expansible fluid thermostat becomes effective

to urge the valve 82 to its closed position against the tension of the spiral spring 94. With the high temperature safety valve 82 moved to its closed position, the supply of fuel gas to the burner 43 is shut off completely irrespective of the pressure and thermostat control to be described, whereby heat is no longer applied to the refrigerating apparatus.

The valve 83 serves to control the main gas supply to the burner 43, and is connected to the diaphragm 67 for movement therewith. The valve 83 and diaphragm 67 are loaded or weighted by metal plates 97 and 98, fixed to opposite sides of said diaphragm.

In order to obtain a pilot flame for the burner 43, there is provided a small pilot burner 100, supplied with fuel gas from a conduit 101, which is connected to a by-pass 102 formed in the casing 66. This by-pass 102 leads from the valve passage 71, so that it will always be in communication with the gas supply from the inlet 73. A suitable spring-pressed adjustable plunger valve 103 may be utilized to regulate flow of gas through this by-pass 102.

In order to operate the valve 83 in accordance with pressure changes in the coils 12, there is provided in the upper part of the casing 66 an expansible pressure diaphragm 110, secured to and in communication with a hollow hub 111. To this hub 111 is connected one end of a capillary tube 112, which extends through an opening in the casing 66, and which connects at its other end into the secondary refrigerating system at a suitable point to sense the pressure in the coils 12. For instance, the capillary tube 112 may be connected at point 113 to the conduit 16 at the inlet side of the condenser 14 as shown in Fig. 1.

In order to make the diaphragm 110 sensitive to pressure changes within the refrigeration range, but still enable it to withstand the high pressures encountered during shut-down periods, it is made of relatively thin hard material, and the movement thereof is limited by an internal stop 114 secured to said diaphragm and extending into the hub 111. This diaphragm 110 may be manufactured by forming two dished discs of beryllium copper in the soft state, sealably securing these discs in opposed relationship by silver soldering and heat treating to maximum hardness.

A spring diaphragm 115, secured to the casing 66 and attached to the hub 111, serves as a guide for the diaphragm 110 in its flexing movement, and also serves as a means for holding the hub 111 up against an adjusting screw 116 threaded in the upper end of said casing. This screw 116 is connected to a control knob 106 provided with a pointer 107, which can be moved over a dial or scale 108 on the casing 66.

Disposed below the pressure diaphragm 110 is a flexible sealing diaphragm 117, used as a safety device to separate the vented space 118 above from the sealed gas space 68 below, so that in case said pressure diaphragm develops a leak, no refrigerant from the secondary system can enter the fuel gas line.

Bleeder gas can enter the gas space 68 from the inlet 73 through a passage 121 interconnecting said space and said inlet. Pressed-in screens 124 are provided in this passage 121, and an adjustable spring-pressed valve plunger 125 is employed in said passage to restrict the flow of bleeder gas therethrough. A screw 126 permits access to this inlet bleeder passage 121 for cleaning purposes.

The bleeder gas flows from the space 68 through

a valve passage 128, communicating with a low pressure line 129. The flow of this gas from the space 68 into the passage 128 is controlled by an outlet bleeder valve 127 operated into open position by the pressure in the diaphragm 110. When this valve 127 is closed, the gas pressure on opposite sides of the diaphragm 67 will be equalized, so that the weighted valve 83 is closed, and the main supply of fuel gas to the burner 43 is cut off. When the valve 127 is opened, the valve 83 will open as will be more fully described, and flow of gas to the burner 43 will be re-established.

The mechanism for operating the outlet bleeder valve 127 from the pressure diaphragm 110 is of the toggle type and includes a lever 130, which is disposed between a pair of fixed spaced bracket flanges 132, and which is pivoted at 131 in V-shaped grooves formed in said bracket flanges. Connected to the intermediate section of the lever 130 is a stud 119, yieldably pressed against the underside of the pressure diaphragm 110 by a spring 136 to be more fully described. The free or movable end of this lever 130 is bent over and cut out in the middle to form a pair of spaced ears provided with pivot grooves 133. A U-shaped trip lever 134 is pivoted at one end in these grooves, and is provided in its bend near the other end with a sharp edged hole 135 to which is hooked one end of the coil spring 136. The other end of this spring 136 is hooked into a sharp edged hole 137 of a valve lever 138. This valve lever 138 is in the shape of a yoke, and has its side arms flanking the trip lever 134, and pivoted in grooves 140 of the fixed bracket flanges 132.

The outlet bleeder valve 127 is attached to the shank section of the lever 138 in such a manner that it will align itself with a valve seat member 141. Two holes 142 are drilled through the valve stem at right angles and countersunk from both sides. Through the lower hole is inserted a pivoting pin 143 located in a recess in the lever 138, and through the upper hole is hooked the end of a spring 144, which holds the valve 127 in place. Upward movement of the lever 138 is limited by a differential adjusting screw 146, threaded in the casing 66, and sealed against gas leakage by a spring-pressed packing 148.

In the operation of the control device so far described, while the refrigerating system is cut-off and the cooling coils 12 defrosting, the valve operating levers 130, 134 and 138 are in the position shown in Fig. 3. In this condition of the valve operating levers, the pivot point 133 will be disposed above the central line of the spring 136, so that the bleeder valve 127 will be closed and the main fuel valve 83 consequently also closed. The distance of this pivot point 133 above the center line of the spring 136 for any predetermined pressure in the diaphragm 110 depends on the setting of the adjusting screw 116.

When the pressure diaphragm 110 expands, the lever 130 moves counter-clockwise about its pivot point 131, so that the left end of said lever moves down until the pivoting point 133 passes below the center line of the spring 136. The lever 134 will then snap upward by the action of the spring 136 into the position shown in Fig. 2. Due to the resultant change in direction of pull by the spring 136 on the lever 138, this lever snaps up until it makes contact with the differential adjusting screw 146 as shown in Fig. 2, thereby opening the valve 127. Due to the small resistance of the outlet bleeder valve 127 and the outlet passage 128 in comparison to the greater resistance of the

inlet bleeder passage 121, the bleeder gas pressure in the chamber 68 is lowered, so that the main valve 83 opens in position shown in Fig. 2 due to the gas pressure on the underside of the main valve diaphragm 67, and the refrigerating system is consequently cut-on.

Although the spring forces acting upon both the snap lever 134 and the valve lever 138 are reversed by the snap action described, the turning moment on lever 130 is always in the same direction urging it into contact with the pressure diaphragm 110. This is due to the fact that the pivoting point 131 is always above the center line of the snap lever 134. Consequently, no return spring is needed.

While the refrigerating system is on, and the controls are in the position shown in Fig. 2, the pressure in the cooling coils 12 will be decreasing, thereby causing contraction of the pressure diaphragm 110. While diaphragm 110 is contracting, the lever 130 is moving clockwise about its pivot axis 131, so that the pivoting point 133 is moving upward from the position shown in Fig. 2 below the center line of the spring 136 to that shown in Fig. 3 above said center line. When the pivoting point 133 reaches above this spring center line, the spring 136 will pull the snap lever 134 downward to the position shown in Fig. 3 in stop engagement with the base of the bracket flanges 132, and due to the resultant change in the position of said spring, the valve lever 138 is also pulled down to close the bleeder valve 127. In this closed position of the valve 127, the main fuel valve 83 will close, and the refrigerating system will be cut-off.

Although the snap action in either valve closing or opening operation has been described as taking place in two steps, actually the two snap actions of each operation take place substantially simultaneously.

The amount of movement required by the pressure diaphragm between the opening and closing snap can be varied by the adjusting screw 146. The further it is backed up as viewed in Fig. 2, the more the diaphragm 110 has to contract before the closing snap occurs, since the distance of the pivot point 133 below the center line of the spring 136 depends on the inclination of the lever 138, which in turn depends on the axial position of the adjusting screw 146.

With the construction of the control device so far described, the cut-on operation of the refrigerating system is controlled by the pressure in the cooling coil 12, and is set for any predetermined coil pressure through adjustment of the screw 116. The cut-off operation of the refrigerating system may also be controlled by the pressure in the cooling coil 12, and be set for any predetermined coil pressure by adjustment of the screw 146. These pressures correspond with the coil temperatures, but have no definite relation to the air temperature in the compartment 11 being cooled. Variations in load could therefore produce variations in the air temperature in said compartment.

In order to effect control of the cut-off operations in response to the actual air temperature in the compartment 11, without affecting cut-on operations in response to pressure in coil 12, the screw 146 has mounted on the upper end thereof a housing 150 for a solenoid 151. This solenoid 151 is desirably operated by low voltage current from a small bell transformer 149, but may be operated also from dry cells or other suitable source of electricity. The screw 146 is provided

with an axial bore 152 for slidably receiving a

plunger 153, having an enlarged soft iron head 154 in the magnetic field of the solenoid 151. The plunger 153 is urged to its uppermost inactive position shown in Fig. 2 by a coil spring 155 in the hollow of the solenoid 151, seated on the top of the screw 146, and bearing against the underside of the plunger head 154. In order to dampen upward return movement of the plunger 153 when the solenoid 151 is de-energized, the plunger head 154 is cup-shaped, and receives a coil spring 156 bearing at its upper end against the solenoid housing 150.

The circuit of the solenoid 151 is controlled in accordance with the air temperature in the compartment 11. For that purpose there is provided an electric thermostat 160 (Fig. 1), which is subject to the air temperature in the compartment 11 as sensed by a thermostat element 161. The electric thermostat 160 is desirably of the heating type, that makes contact upon falling temperature. This is desirable because electric energy will then be consumed only during a short period of each cycle. However, a thermostat making contact upon rising temperature can be used if the solenoid action is reversed.

The electric thermostat 160 is calibrated and adjustable to afford any desired cut-off temperature setting, and has desirably a narrow temperature differential between the closing and the opening of its contact.

While the refrigerating system is on, the control device will be in the position shown in Fig. 2, with the valve lever 138 abutting the screw 146, the bleeder valve 127 open, and the main fuel valve 83 consequently open. During this time, the air temperature in the fixture 11 is going down, and when it reaches a predetermined point as determined by the setting of the thermostat 160, the contact thereof will close. This will energize the solenoid 151, and force the plunger 153 downward against the valve lever 138 to move said lever into valve closed position shown in Fig. 3. The lever mechanism will snap and hold the bleeder valve 127 closed. In the closed position of the bleeder valve 127, the main fuel supply valve 83 will close, and the refrigerating system will be cut-off. The valve lever 138 cannot now open the bleeder valve 127 until actuated by the pressure control mechanism by the expanding action of the pressure diaphragm 110 as described. In the meantime, while the valve lever 138 is down and the bleeder valve 127 is closed, the air temperature in the fixture 11 will rise and when it reaches the thermostatic cut-off point, the thermostatic contact will be opened, the solenoid 151 de-energized and the plunger 153 restored into its uppermost position by the spring 155. This contact closing temperature will be below the temperature at which the refrigerating system will be cut-on by the pressure in the coil 12 as already described.

The cut-on point on the pressure control will be set on the screw 116 to obtain defrosting of the coils, but the cut-off point on the pressure control should be set very low by backing out the differential screw 146 to suit a heavy load. The adjusting movement of the screw 146 may be effected through the turning of the solenoid housing 150, which for that purpose is desirably calibrated and rigid with said screw 146. The screw 146 desirably has a triple thread in order to obtain a comparatively wide pressure range within less than one turn of said screw.

It may happen that the air temperature in the chamber 11 cannot be brought down to the ther-

mostat closing point during an extra heavy load. However, the pressure in the coil 12 will come down, so that the pressure control operating through contraction of the pressure diaphragm 110 will shut off the refrigerating system. This prevents continuous running of the refrigerating system and building up of a heavy frost layer during an extreme load, as would be the case if the thermostat 160 were the only means controlling the cut-off point.

Assuming that the thermostat 160 is set to close at 36° F., when this air temperature is reached, the bleeder valve 127 will be tripped into closed position by the downward actuation of the solenoid plunger 153 as already described. During the resultant off period, the air temperature in the fixture 11 will rise, and if the thermostat 160 has a differential of one degree, the thermostat 160 will snap open and the solenoid plunger 153 will be released when this air temperature reaches 37° F. When the coils 12 have defrosted and the pressure therein increased to the point where the pressure control cuts in, the air temperature in the fixture 11 will be at least a few degrees higher than the thermostat opening temperature. This definitely prevents the solenoid plunger 153 from interfering with the opening snap movement of the bleeder valve 127.

If a thermostat with a wider differential of 3° or 4° F. is used, the pressure control may want to open the bleeder valve 127 before the thermostat 160 has released the solenoid plunger 153. Under these conditions, the solenoid 151 should be made more powerful, so that it can positively hold the bleeder valve 127 closed against the valve opening force produced by the pressure control mechanism to avoid any fluttering or uncertain opening of said valve. The valve 127 will then open when the thermostat 160 releases the plunger 153 upon a further rise in the air temperature in the chamber 11. In no case will the bleeder valve 127 open before the cut-on pressure in the coils 12 has been reached and the defrosting has been completed on each and every cycle.

The control operated from the diaphragm 110 has been described as being directly responsive to the pressure in the cooling coil 12. This pressure has a definite relation to the coil temperature. Therefore, as far as certain aspects of the invention are concerned, the diaphragm 110 may be thermostatically controlled by the temperature of the coil 12. For that purpose, a thermal bulb charged with a suitable volatile fluid may be arranged in thermal contact with the coil 12, and may be connected to the diaphragm 110 by a tube to expand and contract said diaphragm in accordance with the temperature of said coil. Whether the diaphragm 110 is operated by pressure in the coil 12 or thermostatically, it operates according to the temperature of said coil. In the claims therefore, reference to a control responsive to temperature of the cooling element or coil 12, is intended to cover both pressure and thermostatic type of control.

The pilot burner 100 is constructed and arranged so that the main supply valve 83 of the control device 65 closes if for any reason the pilot flame is extinguished. The pilot burner 100 has a valve body comprising a bushing 170, threadedly secured in a valve casing 171. Casing 171 is provided with an inlet passage 172 to which is connected the outlet end of the line 129 from the bleeder valve 127. The bushing 170 is formed with a valve seat 173 cooperating

with a valve 174. Valve 174 is connected to a valve stem 175 which passes through the bushing 170 and is secured to a snap-acting thermostatic diaphragm 176, clamped between the open end of a diaphragm housing 177 and a cover disc 178. A valve passage 180 formed in the bushing 170 communicates with one end of a conduit 181 leading to the burner 43.

A heat conductor 182 is connected to the metallic disc 178, and is adapted to be heated by the pilot flame. When the pilot burner 100 is lit, heat is conducted by the heat conductor 182 to the thermostatic diaphragm 176. Under these conditions, the valve 174 will be open as shown in Fig. 2. When the bleeder valve 127 opens, bleeder gas from the control chamber 68 will flow through passage 128, line 129, valve passages 172, 180, and conduit 181 to the burner.

If the pilot flame is extinguished, the thermostatic diaphragm 176 will snap into a reverse position from that shown in Fig. 2 to close the valve 174. Under these conditions, the opening of the bleeder valve 127 is not attended with lowering of the pressure in the control chamber 68, so that the main supply valve 83 will remain closed.

Various changes and modifications may be made within the scope of the invention as set forth in the following claims.

What is claimed is:

1. In a refrigerator having a storage compartment cooled by an element of refrigerating apparatus operated by a gas burner, a control for said burner including a first valve for starting and stopping flow of gas to said burner, a second valve for causing operation of said first valve, a first control element arranged to operate said second valve to start flow of gas to said burner responsive to increase in temperature of said element and stop flow of gas to said burner responsive to decrease in temperature of said cooling element, and a second control element arranged to operate said second valve only in a direction to stop flow of gas to said burner and responsive to decrease in temperature of air in said compartment.

2. In a refrigerator having a storage compartment and refrigeration apparatus including a cooling element in said compartment, a device controlling operation of said apparatus including toggle mechanism movable in one direction to stop the apparatus and in another direction to start the apparatus, a stop for said mechanism having a movable part, a first element operative responsive to change in temperature of said cooling element to shift said toggle mechanism in both said directions, and a second element operative responsive to decrease in temperature of air in said compartment to move said movable part of said stop to shift said toggle mechanism in only said direction to stop said apparatus.

3. A refrigerator as in claim 2 in which said stop has an opening therein, and said movable part of said stop is movable into and out of said opening.

4. A refrigerator as in claim 2 in which said stop is adjustable.

5. A refrigerator as in claim 2 in which said stop is adjustable and comprises a screw having a passage therethrough, and said movable part of said stop is a rod movable in said passage.

6. A refrigerator including a cabinet having a storage compartment, heat operated refrigeration apparatus including an element for cooling said compartment, a fluid fuel burner for supplying heat for said apparatus, a device controlling operation of said fuel burner including mechanism movable in one direction to stop the burner and movable in the opposite direction to start the burner, a first element operative responsive to decrease in temperature of air in said compartment to move said mechanism only in said direction to stop the burner, and a second element responsive to change in temperature of said cooling element to move said mechanism in both said directions.

7. In a refrigerator having a storage compartment cooled by an element of refrigeration apparatus operated by a gas burner, a control for said burner including a first valve for starting and stopping flow of gas to said burner, a second valve movable in one direction for causing operation of the first valve to start said burner and movable in the opposite direction for causing operation of the first valve to stop the burner, a first control element arranged to operate said second valve in said one direction to start flow of gas to said burner responsive to increase in temperature of said element and in said opposite direction to stop flow of gas to said burner responsive to decrease in temperature of said cooling element, and a second control element arranged to move said second valve only in said direction to stop the burner.

8. In a refrigerator having a storage compartment and refrigeration apparatus including a cooling element in said compartment, a device controlling operation of said apparatus including mechanism movable in one direction to stop the apparatus and in another direction to start the apparatus, a movable member for adjusting said mechanism, a part mounted on and movable relatively of said adjusting member, a first element operative responsive to change in temperature of said cooling element to move said mechanism in both said directions, and a second element operative responsive to decrease in temperature of air in said compartment to move said movable part of said adjusting member to move said mechanism in only said direction to stop said apparatus.

SVEN W. E. ANDERSSON.
